UNITED STATES PATENT OFFICE.

MARIUS E. GRISWOLD, OF BURLINGTON, IOWA

JUVENILE VEHICLE.

1,234,753.

Specification of Letters Patent. Patented July 31, 1917.

Application filed March 19, 1917. Serial No. 155,802

To all whom it may concern:

Be it known that I, MARIUS E. GRISWOLD, a citizen of the United States of America, and a resident of Burlington, county of Des Moines, State of Iowa, have invented certain new and useful Improvements in Juvenile Vehicles, of which the following is a full and clear specification.

The special object of the present invention is to provide a detachable back-rest which will be inexpensive and strong as well as durable in construction and which will preferably be collapsible into a compact condition when it is separated from the vehicle, as more fully hereinafter set forth.

In the drawing—

Figure 1 is a perspective view of my device applied to a child's wagon;

Fig. 2 is a vertical sectional view through the vehicle, looking toward the rear thereof;

Fig. 3 is a plan view of the back-rest detached; and

Fig. 4 is a side elevation of the back-rest in collapsed condition.

Referring to the drawing annexed by reference characters, *a* designates the usual elongated seat board of the vehicle and *b* the hand rails which are spaced away from the longitudinal edges of the seat board and rigidly connected thereto by metal straps *c*. These side rails *b* serve as a support for my improved back-rest which is constructed as follows:

There are two standards *d* at the rear and two standards *e* at the front, the front standards being curved backwardly and merged into the top side bars *f*. Additional side bars *g* connect the front standards to the rear standards, and an additional back bar *h* rigidly connects the rear standards *d*, these bars and standards forming a back-rest which is open at the front and extends along the respective sides of the vehicle and also across the vehicle at the rear thereof.

The back-rest as a whole is supported on the side rails, as above stated, and preferably the connection of the side rails is such that the back-rest structure may be entirely detached from the vehicle. The preferred manner of connecting the back-rest to the side rails is to bend the lower end of each of the standards inwardly and downwardly to form a hook *i*. The distance between the front standards as well as the distance between the rear standards is greater than the distance between the centers of the side rails,

so that when the back-rest structure is in position the standards are approximately on a vertical plane with the outer faces of the side rails, so that the hooks rest directly on top of the side rails and extend around and engage the inner faces of the side rails. The lower portions of the standards are made sufficiently resilient or bendable to enable the back-rest structure to be detached from the side rails by simply springing or bending the lower portions of the standards inwardly. The back-rest structure is prevented from moving backwardly off the hand rails by the rear strap which fastens the hand rails to the seat.

To prevent the back-rest structure from being accidentally disconnected from the side rails, I provide on the outer face of each front standard a stop plate *j* which hangs down far enough to engage the outer face of the rail and thus prevent the standard from being disconnected from the rail by being pushed inwardly. These stop plates *j* are pivotally connected to the standards so as to permit them to be swung upwardly out of the way when it is desired to separate the back-rest structure from the vehicle.

The upper ends of the standards *d* are pivotally connected to the rear ends of the side bars *f*, and the forward ends of the side bars *g* are pivotally connected to the front standards, while the rear ends of the side bars *g* are pivotally and slidably connected to the rear standards, whereby the back-rest structure is rendered capable of collapsing into a compact space, as shown in Fig. 4. The sliding connection between bars *g* and the rear standards is formed by a longitudinal slot *k* made in each of the side bars and a pin or rivet *l* extending through the slot and fastened to the standard, the rear end of the slot being turned upwardly slightly to permit the entrance thereto of said pin *l* when the seat structure is extended or folded, and thus lock the seat structure in its unfolded condition.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

The nature and scope of the invention having been thus indicated and its preferred embodiment having been specifically described, what is claimed as new is:

- 5 1. The combination with a child's vehicle provided with a hand-rail along each longitudinal edge of its seat board, bars being provided for supporting these hand-rails on the seat board, of a back-rest structure provided with devices at its lower side for engaging said rails slidably, whereby said back-rest may be arranged to bear against said rail-supporting bar at the rear to thus limit the backward movement of the back-rest.
- 10 2. The structure recited in claim 1, the devices on the back-rest for engaging the hand rails being hooks which are bent inwardly and downwardly and outwardly to thus support the back-rest on the hand-rails and to partly surround the same, the parts of the back-rest carrying the two forward hooks being capable of being pressed inwardly to detach said hooks from the hand-rails.
- 15 3. A back-rest for a child's vehicle having hand-rails at its side edges consisting of standards and connecting bars, each of the standards being provided at its lower end

with a hook formed by curving the lower end of the standard inwardly and downwardly and outwardly to thereby partly surround the inner surface of the hand-rail, the lower ends of the standards being bendable inwardly to thereby permit the back-rest structure to be detached from the hand-rails.

4. The structure recited in claim 3, movable locking means being provided on the front standards to prevent accidental detachment of the seat structure from the vehicle.

5. A back-rest structure for vehicles, embodying front standards and also rear standards, pairs of side bars as well as transverse back bars connecting the standards, the lower side bars being pivotally connected to the front standards and pivotally and slidably connected to the rear standards, said rear standards being pivotally connected to the top side bars, thereby rendering the back-rest structure collapsible.

6. The structure recited in claim 4, said movable locking devices consisting of laterally-swinging depending links pivoted to the exterior faces of the standards.

In testimony whereof I hereunto affix my signature.

MARIUS E. GRISWOLD.
